LEATHER OR SIMILAR ARTICLE

Frank Hiltenbrand, Weehawken, N. J.

Application June 19, 1942, Serial No. 107,239

Term of patent 3½ years

To all whom it may concern:

Be it known that I, Frank Hiltenbrand, a citizen of the United States of America, residing at Weehawken, in the County of Hudson and State of New Jersey, have invented a new, original and ornamental Design for Leather or Similar Article, of which the following is a specification, reference being had to the accompanying drawing, constituting a part thereof.

The figure is a plan view of a piece of leather or similar article showing my new design.

I claim:

The ornamental design for leather or similar article, as shown.

FRANK HILTENBRAND.
